CLAIM

The ornamental design for a humidor cabinet furniture with display screen, as shown and described.

DESCRIPTION

FIG. 1 is a front view of a humidor cabinet furniture with display screen, showing the new design;

FIG. 2 is a left view thereof;

FIG. 3 is a rear view thereof;

FIG. 4 is a right-side view thereof;

FIG. 5 is a top view thereof;

FIG. 6 is a bottom view thereof;

FIG. 7 is a front perspective view thereof;

FIG. 8 is a bottom perspective view thereof; and

FIG. 9 is a front perspective view of the humidor cabinet furniture with display screen, shown with the doors in an open state.

Broken lines indicate portions of the article that form no part of the claimed design.

1 Claim, 6 Drawing Sheets
